UNITED STATES PATENT OFFICE.

JOHN J. A. MILLER, OF DENVER, COLORADO.

FUEL-SAVING ATTACHMENT FOR FURNACES.

1,379,873.

Specification of Letters Patent.

Patented May 31, 1921.

Application filed July 19, 1919. Serial No. 311,946.

To all whom it may concern:

Be it known that I, JOHN J. A. MILLER, a citizen of the United States of America, residing at the city and county of Denver 5 and State of Colorado, have invented a new and useful Fuel-Saving Attachment for Furnaces, of which the following is a specification.

This invention relates to improvements in 10 fuel saving attachment for furnaces.

The object of the invention is to provide an attachment for the doors of all classes of furnaces, whereby a regulated supply of heated atmospheric air is admitted to the 15 combustion chamber of the furnace for a predetermined period after the coaling operation, the said air being discharged in a thin sheet over, and a slight distance above the coal bed, by which it is intimately 20 mixed with the combustible gases and the floating particles of carbon and tar, thus causing complete combustion of these particles, and the consequent elimination of the unconsumed product, or smoke.

25 Further, to provide an attachment of this character, which can be applied to furnace doors of the commonly employed type, at a relatively small expenditure of time and expense, and which effects a maximum saving 30 of fuel, together with the practical elimination of smoke.

Further, to provide an attachment for furnace doors, for the purpose above stated, which comprises an air receiving chamber, 35 a damper for admitting a volume of air thereto for a predetermined period after the coaling operation and thereafter limiting the air supply to a predetermined quantity, the said chamber having an outlet into the 40 combustion chamber, the area of which can be increased or diminished to meet conditions, whereby a regulated supply of air can be admitted to the said combustion chamber in such manner as to intimately mix with 45 the combustible gases therein, and thus effect complete combustion of the fuel.

These objects are attained by the mechanism illustrated in the accompanying drawings, in which:

50 Figure 1 is a vertical, longitudinal, sectional view, through the fire door and a portion of the front wall of a furnace, showing the improved device attached to the said fire door.

55 Fig. 2 is a front view thereof the damper releasing lever being in the position it

reaches immediately prior to releasing the said damper.

Fig. 3 is a side view of the same.

Fig. 4 is a rear view of the air heating 60 chamber.

Fig. 5 is a front view of the automatically operating damper which admits air to the heating chamber.

Fig. 6 is a central, longitudinal, sectional 65 view of the same.

Fig. 7 is a side view of the lever operated arm for turning the damper to an open position.

Fig. 8 is a perspective view of one of the 70 adjustable nozzle sections for varying the area of the air outlet; and

Fig. 9 is a top view of the gravity lever for raising the arm shown in Fig. 7, and for effecting the release of the damper whereby 75 the same is permitted to turn to a closed position.

Visible furnace smoke can only be abated by effecting complete combustion in the furnace, of the floating particles of carbon 80 and tar, and this complete combustion is accomplished only by supplying air sufficient for the complete oxidation of all combustible matter, and the intimate mixing of the air with the combustible gases and the 85 floating particles of carbon and tar. To bring about this result, air in large quantities should be admitted over the fire immediately after coaling and this quantity should be gradually reduced as the distillation 90 of the volatile combustible nears completion.

The improved furnace door attachment is adapted to meet these requirements by means of a combination of elements, which 95 are arranged and constructed as follows:

Referring to the accompanying drawing:—The numeral 1 indicates the front wall of an ordinary furnace, and 2 the fire door, to which the present invention is secured. These doors, as ordinarily constructed, have a circular group of air inlet holes, which are opened or closed by a damper, and in order to attach the invention, that part of the door surrounded by the 100 circular group of holes is first removed, leaving a circular opening 3, in the door, as shown in Fig. 1, such an opening being formed in new doors to which the attachment is to be secured.

110 A short air inlet pipe, 4, is inserted through this hole, and this pipe is centered

and supported in the following manner:—
 A washer, 5, is secured upon each side of the door, and these washers have central apertures of a size to receive the pipe, 4, 5 the size of the said pipe varying to suit the size and capacity of the furnace upon which it is used. Washers 6 and 7 are then placed on the pipe, the washer, 6, abutting against the adjacent washer, 5, while the washer, 7, 10 acts as a clamp to secure one end of an air box, 8, to the furnace door. The pipe, 4, is externally threaded for a portion of its length to receive clamping nuts, 9 and 10, the nut, 9, being screwed against the washer, 15 6, while the nut 10, is screwed against the washer, 7, and this washer rests against an introverted flange 11, on the air box and clamps the same against the adjacent washer, 5. Thus, the pipe, 4, is centered 20 in the door by the washers 5, 6, and 7, and held in place by the nuts, 9 and 10, which are clamped against the washers on opposite sides of the door.
 Within the pipe, 4, is pivotally mounted 25 a damper, D, which comprises a supporting rod, 12, which extends through oppositely positioned holes in the pipe, and a plurality of centrally apertured concentrically arranged disks, 13, which vary progressively in size and are secured one upon 30 another to the rod. Three of these disks are illustrated, but as many more may be used as may be found necessary. The holes in the disks also vary in diameter in proportion 35 to the diameter of the disk, and the function of the damper is to admit a supply of air to the combustion chamber of the furnace, between the coaling periods, sufficient to effect the complete combustion. As the 40 amount of air necessary for this purpose varies according to the size and capacity of the furnace, the necessary amount must be determined in each case, and this is easily ascertained by the improved-multiple-disk 45 damper.

In the arrangement of the disks, each added disk decreases the diameter of the air inlet aperture, as the topmost disk is the smallest disk, and also, has the smallest aperture, while the largest disk is of the same diameter as the interior of the pipe, 4, and the holes in the disks vary progressively from the largest to the smallest. Thus, by adding or removing disks, an aperture, giving the necessary air supply, may be ascertained, and the supply is determined in each individual case.

One end of the damper rod, 12, extends a slight distance beyond the face of the 60 pipe, 4, and is formed with a shoulder, 14; and the other end portion of the rod is slightly reduced in diameter to form a shoulder, 15, which bears against a bearing, 16, through which the said reduced end portion 65 passes, and upon the outer end of this re-

duced portion is rigidly secured a tappet, 17, comprising a short arm, having a projection, 18, extending at right angles thereto and adapted to be engaged, in a manner to be presently described, to swing the damper 70 to an open position, as shown in Figs. 1 and 2 and tending by its weight, to turn the damper to closing position.

The lower end of a blade spring, 19, is bolted to the furnace door, and the upper 75 end of this spring is apertured to receive that end of the rod, 12, having the shoulder, 14, against which the spring bears and with which it is held in frictional engagement by a contraction coil spring, 20, one end of 80 which is secured to the said blade spring, while the other end thereof is secured to a pin projecting from the pipe, 4.

By reference to Fig. 2, it will be understood that when the damper is turned to its 85 open position, the blade spring, 19, bearing frictionally against the shoulder, 14, of the rod, 12, causes its shoulder, 15, to bear frictionally against the bearing, 16, by which the rod is held against turning, and the 90 damper is thus held open until the blade spring, 19, is sprung out of engagement with the shoulder, 14, when the damper swings by gravity to a closed position.

The spring, 19, is sprung to release the 95 damper in the following manner:—A lever arm, 21, is pivotally mounted on the fire door, by a bolt, 22, which extends through the adjacent washer, 5, and also through the door. The inner end of this lever carries a roller, 23, and the outer end portion of the lever is threaded to receive counter-balancing weights, 24. The pivotal point of the lever is adjacent the end having the roller 23, so that the preponderance of the 100 weight of the lever is on the opposite side of its pivot bolt from the roller, 23.

A segmental rack, 25, is formed on the under side of the lever, the axis of whose arc is the pivot bolt, 22, and this rack meshes 110 with a gear wheel, 26, which is mounted on a bolt, 27, which is screwed into the fire door. An expansion coil spring, 28, surrounds the bolt between its head and the face of the gear wheel, 26, and by turning the bolt the tension of the spring, 28, is increased or diminished, and the pressure of the spring against the wheel prevents easy rotation of the same, as the hub of the wheel is in frictional contact with the fire 115 door. Thus, when the outer end of the lever is raised, the weights, 24, will cause the lever to descend by gravity, but the length of time required for its descent is determined by the wheel, 26, the rapidity of 120 the rotation of which is determined by the tension of the spring, 28.

An arm, 29, of the form shown in Fig. 7 is pivotally attached to the lever, 21, the arm having an opening, 30, through which the 125

lever passes, and in which it is secured by a pin, 31, as shown in Fig. 2. The upper portion of the arm passes through a guide, 32, and the upper end of the arm is adapted 5 to engage the tappet, 17, and swing the damper to the position shown in Fig. 2, when the lever, 21, is raised by the fireman, which is done when he opens the fire door to shovel in coal.

10 The lower end of the arm, 29, terminates in a foot, 33, which is adapted to be engaged by a projection, 34, on a hand lever, 35, which is pivotally secured to a bracket, 36, which is bolted to the fire door. The 15 lower end of the hand lever extends beyond the lower edge of the door, and this end may be either engaged by a shovel in opening the door, or it may be grasped by the fireman, and the lever is swung around until 20 a stop, 37, on its upper end engages the door, when further turning of the lever is prevented, and by giving the lever both a pulling and lifting action, the door latch, 38, is released from its keeper 39 and the 25 door is swung open.

When the stop, 37, engages the door, the arm, 29, is raised high enough to swing the tappet to the position shown in Fig. 3, and open the damper, D, and the damper remains 30 open until the lever, 21, drops to its lowermost position, when the roller, 23, in its inner end engages a cam, or projection, 40, on the blade spring, 19, by which the spring is sprung or forced out far enough 35 to disengage the shoulder, 14, on the damper rod, 12, thus permitting the damper to swing to a closed position.

If it takes on an average about half a minute to fire the furnace, and it has been 40 found that the damper should be left open for about three minutes after firing; then, the spring, 28, should be given a tension by the bolt, 27, that will retard the rotation of the gear wheel 26, to such an extent 45 that the lever will require three and one-half minutes to swing from its raised position to its normal or horizontal position. The downward swinging movement of the lever is limited by the engagement of the 50 foot, 33, on the arm, 29, with the projection, 34, on the hand lever, 35, and this occurs after the roller, 23, engages the cam, 40, on the blade spring, 19, as will be understood by reference to Fig. 2. In timing the 55 drop of the lever, 21, the weights, 24, are also adjusted on the lever to assist in determining the drop.

The air box, 8, is rectangular in cross section and is preferably made in two sections, the forward section 8^A, being semi-cylindrical in form, and being made of material that will stand continuous high temperature. This section is provided with an air outlet slot, 41, through which air is 60 charged above the coal bed into the com-

bustion chamber, 42. The area of this slot is adapted to be contracted, when necessary, by nozzle sections, 43, which are of the same length as the slot, 41, and have overlapping ends which permit the sections to slide one 70 upon the other, as will be understood by reference to Fig. 4. Each of these nozzle sections is formed with a curved plate member, 44, which conforms to the curvature of the section 8^A, and each member, 44, is 75 provided with slots, 45, through which pass screws, 46, which are screwed into the section 8^A. By partially unscrewing these screws, the nozzle sections can be adjusted to vary the size of the slot, 41, and the 80 screws are then turned to clamp the members, 44, to the section 8^A, to hold the sections in their adjusted positions. The nozzle has a slight downward inclination from the air box, in order to direct the air against 85 the coal bed, and the air is heated to a high temperature in the air box before passing out through the nozzle. The upper nozzle section may be somewhat longer than the lower section in order to more effectively 90 direct the air over the coal bed, and the nozzle prevents diffusion of the air, which is delivered over the coal bed in a thin sheet, causing it to thoroughly mix with the combustible elements and thus insure complete 95 combustion.

By constructing the air box in two sections, the section 8^A which is subjected to the greatest heat, can be removed, when necessary, and replaced with a new section.

Having described my invention, what I claim as new and desire to secure by Letters Patent, is:

1. In combination with a furnace door, of means defining an air passage therethrough, means for controlling the flow of air therethrough, means operative when the door is being opened to actuate the controlling means so as to permit free passage of air, means tending to hold the controlling 105 means in open position, means tending to move the controlling means to closing position and time-controlled means set for operation when the door is opened for automatically releasing the controller-holding 110 means.

2. In combination with a furnace door, of means defining an air passage therethrough, a damper for controlling the flow of air therethrough, means for opening the 120 door, means in co-operative relation with the said opening means for effecting the opening of the damper when the door is opened, means tending to hold the damper in open position, means tending to close it and time-controlled means in co-operative relation 125 with the door-opening means and adapted to be set, when the door is being opened, to automatically release the damper-holding means.

3. In combination with a furnace door, means defining an air passage therethrough, a damper for controlling the flow of air therethrough, a handle having angular play for opening the door, means for translating the angular motion during opening of door for opening the damper, means tending to hold the damper in open position, means tending to close the damper, time-controlled means for automatically releasing the said damper-holding means and means for translating the angular motion of the handle to said time-controlled means to set it for operation when the door is opened.
4. In combination with a furnace door, means defining an air passage therethrough, a damper for controlling the flow of air therethrough, a handle having angular play for opening the door, an element in the path 20 of movement of the handle for opening the damper, means tending to hold the damper in open position, means tending to close the damper, a pivotally mounted lever connected with said element and adapted to be turned when the handle is moved to open the door, means on the lever for causing it to return to its normal position, means for retarding the returning motion and means on the lever adapted to engage, near the end of 25 its returning motion, the damper holding means to release it.
5. In combination with a furnace door, means defining an air passage therethrough, a damper for controlling the flow of air therethrough, a handle having angular play for opening the door, a weighted crank on the damper for operating it, an element in the path of motion of both the said handle and the crank and so related thereto that 30 upon moving the handle to open the door
- the damper is opened, means for frictionally holding the damper in open position, a pivotally mounted lever connected to the said element and adapted to be angularly moved thereby when the handle is operated, means 45 for causing the lever to return to its normal position, means for retarding such returning movement and means connected with the lever to act, near the end of the returning motion thereof, upon the said frictional means to release it.
6. In combination with a furnace door, means defining an air passage therethrough, a damper for controlling the flow of air therethrough, a handle having angular play for 50 opening the door, a lever pivotally mounted on the door in a normally horizontal position, a crank on the damper for operating it, an upright element loosely mounted upon the said lever in the path of motion of the handle and the crank, the parts being so related that when the handle is moved to open the door, the said element is moved upwardly into contact with the crank causing the damper to open and the lever is turned 55 upwardly out of its normal position, means for frictionally holding the damper in open position, means for returning the lever to its normal position, means for retarding such return movement and means connected 60 with the lever to act, near the end of its return motion, upon the said frictional means to release it.
- In testimony whereof I affix my signature in presence of two witnesses.
- JOHN J. A. MILLER.
